UNITED STATES PATENT OFFICE.

GUSTAVE EDWARD MEYER, OF NEW MEADOWS, IDAHO.

LEAF TURNER.

Application filed May 28, 1925. Serial No. 33,547.

This invention relates to leaf turners and has for its main object the provision of a simple device whereby a musician will be enabled to turn the leaves of a book or of a composition without any perceptible pause in the playing. The invention seeks to provide a device for the stated purpose which may be easily applied to the desk of a piano or to a music stand and by which the leaves or music sheets will be held in proper position to permit ready reading of the notes and may be quickly turned when the end of a page has been reached in the playing. The invention is illustrated in the accompanying drawings and will be hereinafter fully set forth.

In the drawings:

Figure 1 is a view, partly in vertical section and partly in end elevation, of a piano desk having my leaf turner mounted thereon;

Fig. 2 is a front elevation of the leaf turner;

Fig. 3 is a top plan view of the same;

Fig. 4 is a front elevation showing one of the leaf-carrying bars swung into the position assumed after turning the leaf;

Fig. 5 is a top plan view of the device with the parts in the position shown in Fig. 4;

Fig. 6 is a detail section on the line 6—6 of Fig. 2;

Fig. 7 is a detail section on the line 7—7 of Fig. 2;

Fig. 8 is an enlarged detail plan view of the finger lever by which the device is manipulated;

Fig. 9 is a detail section on the line 9—9 of Fig. 2, and

Fig. 10 is a view similar to Fig. 2 but showing a different form of the invention.

Referring more particularly to Fig. 1, the numeral 1 indicates a piano desk to which the device is applied. In carrying out the invention, I secure to the desk 1 at a proper point in the height thereof a bail or loop 2 in which is fitted the lower end of a supporting plate or standard 3 which has its lower end offset, as shown at 4, whereby the upper portion of the said supporting bar or standard will be set out from the desk and marring of the desk will be thereby prevented. The upper end of this standard 3 is fitted in a loop or flattened eye 5 on the rear side of a base bar or plate 6 and a set screw 7 is mounted in the said bail or eye whereby to secure the base bar to the support. The said base plate or bar extends laterally with respect to the support so that its greater length is disposed at the right of the support in front of the piano desk, and projecting forwardly from the upper and lower edges of the said base member are lugs 8 in and between which is fitted a pin 9 upon which the leaf-carrying and turning arms 10 are pivotally mounted. As shown most clearly in Figs. 2 and 4, springs 11 are coiled around the pin 9 and have their ends extended laterally to bear respectively against the front face of the base member 6 and the rear faces of the respective arms 10 when the said arms are in their initial positions so that, if the arms be released, the force of the springs will be exerted to swing the arms about their pivots to the left side of the central support. Each arm 10 is equipped with depending spring clips 12 which are adapted to engage the upper edges of the respective leaves or sheets of the music so that each bar will hold one music sheet or leaf. I also provide at the outer end of each arm 10 a light rod 13 which is adapted to bear against the back of the sheet or leaf before it is turned whereby the sheets or leaves will be positively separated and after a leaf has been turned the proper rod or support 13 will rest upon the edge of the same so that it will be held flat and will be prevented from fluttering to interfere with the reading of the music. In order that a book may be positively held open upon the piano desk or the music stand, similar holding members 14 are attached to and depend from the opposite ends of the base plate 6, as clearly shown in Fig. 2.

The arms 10 are normally held at the right of the device by a catch 15 which is preferably in the form of a leaf spring having one end 16 secured to the base bar 6 upon the back thereof and having the greater portion of its length extending forwardly through an opening 17 in the base bar where-by the pendent tooth 18 at the front end of the catch is adapted to engage over the upper edge of the front arm and retain the same in a position substantially parallel with the base member, as will be readily understood upon reference to Figs. 3 and 6. To release the catch 15 from the arm 10 so that the arm may swing to the opposite side of the device, I provide a rocking arm or lever 19 which is pivotally mounted between its ends upon the front face of the base member 6 and has its inner end disposed im-

mediately below the end of the catch 15, as clearly shown. The outer end of the lever is enlarged vertically to form a head 20 and to the lower end of said head is attached a 5 chain or light wire 21 which extends downwardly to a position immediately above the piano keys or to the base of a music stand. The lower end of this flexible connection is attached to a presser 22 which may be secured 10 in any convenient or preferred manner to the fall board 23 of the piano or the base of the music stand. This presser piece consists essentially of a short lever 24 fulcrumed at its inner end to a holding bracket 15 25 and normally held by a leaf spring 26 in such position that the flexible connection 21 will be taut and the lever 19 will respond instantly to any pressure exerted upon the said presser member. In the upper portion 20 of the head 20 is formed an opening 27 which accommodates a second spring catch 28 similar to the catch 15 and extending through an opening 29 formed in the base plate 6 adjacent the right-hand end of the 25 same. The spring latches 15 and 28 are so proportioned and disposed that the catch 15 will normally engage the upper edge of the front turning arm 10 while the free working end of the latch 28 will be disposed 30 above said arms, as clearly shown in Figs. 6 and 7. When a leaf is to be turned, a downward pressure is exerted upon the presser member 22, thereby pulling downwardly upon the head 20 of the lever 19 and rocking 35 said lever so that the catch 28 will be caused to engage the inner or rear turning arm while the catch 15 will be released by the inner end of the lever from the front turning arm, whereupon the latter arm will at 40 once swing to the left and turn the sheet. When the pressure upon the member 22 is released, the force of the spring 26 and of the spring catch 28 combine to return the lever 19 to its initial position withdrawing 45 the catch 28 from the rear turning arm and permitting the catch 15 to engage said arm.

In order that the leaf-carrying arms may be held against accidental turning when the device is not in use, I provide a hook 30 50 which is hung on the bar 6 at the end thereof in position to engage over the arms. When not in use, the hook hangs free back of the leaf-carrying arms.

It is frequently desirable to have means, 55 additional to the rods 13, for holding the sheets or leaves flat and the pendent bar 31, or the bar 32, may then be employed. The device shown in Fig. 2 is adapted particularly for use with loose sheets and includes 60 a clasp 33 carried by the lower end of the bar 31 and extending laterally to engage and hold the side edge of the sheet. The clasp is held upon the bar by a pin or rivet 34 and, between the clasp and the bar, a lateral arm 35 is pivotally mounted upon said 65

pin or rivet so as to fold over upon the bar or extend laterally therefrom as desired. When extended laterally, as shown in Fig. 2, the arm 35 will pass behind the sheet engaged by the clasp 33 and aid in turning 70 the same so as to avoid tearing at the point of engagement of the sheet by the clasp.

When the device is used in connection with a book, the clasp 33 is, of course, unavailable, and the structure shown in Fig. 75 10 is employed. In this form, arms 36 are formed integral with or rigidly secured to the pendent bar 32 and the bar and arms are placed back of the leaf to support and aid in turning the same. In both forms, the 80 several elements will be so proportioned as to avoid obscuring any of the notes or other musical characters.

The several clasps 12 are shown provided with hooks 37 engaged through slots 38 in 85 the leaf-carrying arms and the bar 32 is shown as equipped with a clasp 39 clamping the leaf-carrying arm but other means for suspending the parts upon the arm may be employed. To prevent jamming of the 90 front leaf-carrying arm against the rear arm, a stop lug 40 is provided on the front side of the rear arm.

While the device is shown mounted upon a piano, it may be mounted upon a music 95 stand without any substantial structural change.

It is thought the operation of the device will be readily understood from what has been said. The book or music sheets are placed upon the piano desk or the music stand in the usual manner and the clasps 12 of the respective turning arms are engaged with the upper edges of the respective sheets so that the front arm 10 will carry the 105 front leaf which may have to be turned and each turning arm will carry one leaf or sheet. The catch 15 is long enough to extend across all the turning arms and engage over the upper edge of the foremost arm, as 110 shown in Figs. 2 and 6, and it will be understood that any preferred number of arms

may be provided although two arms will usually be sufficient. When a pull is exerted upon the flexible connection 21, as before stated, the foremost arm 10 will be released from the catch 15 and the spring 11 engaging said arm will at once swing it over to the left side of the device so that the music will be turned 115 promptly and so quickly that continuous reading of the music is possible and the performance is not perceptibly interrupted. When the front turning arm is released, the next turning arm tends to swing under the influence of its spring 11 but the latch 28 will be lowered by the action of the lever 19 so that it will engage said second arm and prevent the complete turning of the same. When the presser 22 is released, the lever 19, 120 of course, rocks to its initial position, push- 125

ing the catch 28 upward to release the turning arm and permitting the catch 15 to spring into the path of the same to hold it.

My device is exceedingly compact and simple and may be produced at a low cost. It may be applied to any piano or music stand and will operate efficiently at all times.

Having thus described the invention, I claim:

- 10 1. A leaf turner comprising a support including a laterally extending base member, a plurality of leaf-turning arms pivotally mounted upon the base member, means on each arm to hold a leaf, means to swing the arms, a plurality of latches independently secured upon the base member in spaced relation longitudinally of the base member and extending forwardly therefrom over the arms to engage the arms, and a releasing device mounted upon the base member between the latches and engageable with said latches whereby to release one latch from the front turning arm and simultaneously engage the other latch with the next inner turning arm.
- 15 2. A leaf turner comprising a support including a laterally extending base member provided with longitudinally spaced openings therethrough, spring latches secured independently upon the back of the said base member and extending forwardly through the respective openings therein, a plurality of turning arms pivotally mounted upon the base member and normally extending along the base member under said latches to be engaged thereby, means upon the base member to swing the respective arms when released from the latches, and a trip member pivotally mounted upon the base between

the latches and simultaneously actuating the latches in opposite directions whereby to release one latch from the foremost turning arm and engage the other latch with the next inner turning arm.

3. A leaf turner comprising a support including a laterally extending member provided with longitudinally spaced openings therethrough, spring latches secured independently upon the back of the member and extending forwardly through the respective openings, a plurality of turning arms pivotally mounted upon the said member and normally extending along the same under the latches whereby the latches may engage over the upper edges of the arms, means upon the supporting member to swing the respective arms when released from the latches, a trip lever pivoted between its ends to the supporting member between the latches and having one end disposed under the adjacent latch to bear against the same and its opposite end provided with an opening to receive the other latch, the first-mentioned latch normally engaging over the foremost turning arm and the last-mentioned latch being normally held out of engagement with the arm by the trip member, and means for rocking the trip member whereby the first-mentioned latch will be released from the foremost turning arm and the second-mentioned latch will be simultaneously engaged with a second turning arm to prevent swinging movement of the latter.

In testimony whereof I affix my signature.

GUSTAVE EDWARD MEYER. [L.S.]
